United States Patent Office

Des. 190,724
Patented June 27, 1961

190,724

TRUCK

Robert E. Heyman, 2455 Seymour Ave., Union, N.J.

Filed Sept. 1, 1960, Ser. No. 61,986

Term of patent 14 years

(Cl. D14—3)

Fig. 1.

Fig. 2.

FIG. 1 is a front perspective view of a truck showing my new design;

FIG. 2 is a rear perspective view thereof.

The dominant features of my design are shown in full lines.

I claim:

The ornamental design for a truck, as shown and described.
